(57) **CLAIM**

What is claimed is the ornamental design for a paddle blade notch, as shown and described.

DESCRIPTION

FIG. 1 is a rear perspective view showing a paddle blade notch of Applicant's invention.

FIG. 2 is a front perspective view of the paddle blade notch of FIG. 1.

FIG. 3 is a top plan view of the paddle blade notch of FIG. 1.

FIG. 4 is a right side elevational view of the paddle blade notch of FIG. 1.

FIG. 5 is a left side elevational view of the paddle blade notch of FIG. 1.

FIG. 6 is a bottom plan view of the paddle blade notch of FIG. 1.

FIG. 7 is a front elevational view of the paddle blade notch of FIG. 1; and,

FIG. 8 is a rear elevational view of the paddle blade notch of FIG. 1.

The dash-dash broken lines shown in the drawings illustrate portions and environment of the paddle blade notch that form no part of the claimed design.

The dash-dot broken lines shown in the drawings illustrate the boundary of the paddle blade notch that form no part of the claimed design.

1 Claim, 3 Drawing Sheets
